DESIGN FOR A COMBINATION HAND MIRROR AND CLOCK

Assunta Delucchi, San Francisco, Calif.

Application April 26, 1944, Serial No. 113,381

Term of patent 7 years

(Cl. D86—10)

To all whom it may concern:

Be it known that I, Assunta Delucchi, a citizen of the United States, residing in the city and county of San Francisco and State of California, have invented a new, original, and ornamental Design for a Combination Hand Mirror and Clock, of which the following is a specification, reference being had to the accompanying drawing, forming a part thereof.

In the accompanying drawing:
Fig. 1 is a side elevation of a combination hand mirror and clock, embodying my new design;
Fig. 2 is a front view of the same; and
Fig. 3 is a rear view of the same.

I claim:

The ornamental design for a combination hand mirror and clock, substantially as shown.

ASSUNTA DELUCCHI.
